UNITED STATES PATENT OFFICE.

JOHN BOTTS, OF LANE, KANSAS.

WASHING-MACHINE.

1,297,071.

Specification of Letters Patent. Patented Mar. 11, 1919.

Application filed June 28, 1918. Serial No. 242,423.

To all whom it may concern:

Be it known that I, JOHN BOTTS, a citizen of the United States, and a resident of Lane, in the county of Franklin and State of Kansas, have invented certain new and useful Improvements in Washing-Machines, of which the following is a specification.

This invention relates to washing machines of the rotary cylinder type, and an object of the invention is to provide a washing machine as specified which will thoroughly cleanse clothing, requiring the utilization of a minimum quantity of detergent liquid and one in which the rotary cylinder is provided with a plurality of pivoted sections opening out at its periphery, which sections are held in various closed clamping positions by suitable adjusting means to cause them to securely grip a piece of clothes or fabric to be washed, causing it to lie against the outer corrugated surface of the rotor and be moved about within a cylindrical casing or housing which carries a circular relatively stationary rubber having its inner surface corrugated which relatively stationary rubber is yieldably supported by means of flat and helical springs and is itself constructed of resilient material to prevent yielding movement thereof upon variations of the size of the clothing or article being washed engaging thereagainst and also to maintain a rubbing engagement with the article being washed at all times.

Other objects of the invention will appear in the following detailed description, taken in connection with the accompanying drawings, forming a part of this specification, and in which drawings:

Figure 1 is a side elevation of the improved washing machine.

Fig. 2 is a vertical section through the washing machine.

Fig. 3 is a transverse vertical section through the washing machine.

Fig. 4 is an end view of the rotary cylindrical rubber.

Fig. 5 is an end view of the rotary rubber illustrating the end opposite to that shown in Fig. 4 of the drawings.

Fig. 6 is a detail view of the rod used in the construction of the washing machine.

Fig. 7 is a detail perspective view of a catch structure employed for facilitating in maintaining a pivoted article gripping section in adjusted position.

Referring more particularly to the draw-

ings, 1 indicates the casing or supporting body of the machine as an entirety, which is supported by suitable supporting legs 2 and has handles 3 connected thereto. The casing 60 1 is formed of the lower retaining portion 4 and the cover 5 which is hingedly connected as shown at 6 to the lower portion 4. A shaft 7 extends transversely through the center of the casing 1 which casing is cylindrical in 65 shape and has a rotor or rotary rubber 8 mounted thereon. The rotary rubber 8 includes a plurality of spaced disks 9 which have segments 10 cut therefrom and pivotally connected as shown at 11 to the main 70 portions of the disks. These segments, together with the peripheries of the disks have teeth 12 of corrugated galvanized iron or sheet metal attached thereto to provide an article rubbing surface. A plurality of 75 rods 13 extend transversely through the disks 9, one rod being provided for each of the pivoted segments 10. The ends 14 of the rods 13 are bent to form loops 15 and straight portions 16. The loops 15 have 80 links 17 connected thereto which links are in turn connected as shown at 18 to the pivoted segments 10 while the straight portions 16 of the ends 14 of the rods 13 extend across the ends of the outermost disk 9' and engage 85 beneath the ratchet teeth 19 formed upon angled plates 20 which are attached to the disk 9'. By providing a plurality of ratchet teeth 19, an adjustable connection between the pivoted segments 10 and the end disk 9' 90 is provided to permit adjustment of the pivoted segments to securely grip an article to be washed by the machine.

The ends of the rods 13 which project through the end disk opposite to the disk 9' are angled as shown at 22 and are engaged by eyes 23 formed upon the ends of links 24 which are pivotally connected as shown at 25 to the pivoted segments 10 and by provision of the pivoted links 24 and the pivoted links 17, together with the rods 13 the pivoted segments 10 may be drawn and held for securely gripping a piece of clothes or article to be washed between the facing edges indicated at 26 of the segments 10 and 105 the disks 9.

A relatively stationary rubber generically indicated by the numeral 30 is positioned within the casing 1 for co-action with the rotary rubber, to thoroughly cleanse articles 110 to be washed. The stationary rubber 30 is composed of sections 31 and 32, which latter

section is carried by the cover section 5 of the casing. The sections 31 and 32 are arranged to form a continuous cylindrical relatively stationary rubber when the cover 5 is closed.

The sections 31 and 32 of the relatively stationary rubber comprise corrugated concaved plates 33 formed preferably of corrugated sheet metal which are carried by suitable 10 silent bars 34 that are spaced from each other as clearly shown in Fig. 3 of the drawings. Flat springs 35 are attached to the inner surface of the sections 4 and 5 of the casing 1 and have their inner free ends bearing against the bars 34, as clearly shown in Fig. 2 of the drawings. Helical springs 36 engage against the under or outer surfaces of the free ends of the flat springs 35 and assist these flat springs in yieldably supporting the corrugated plates 33 in their innermost 15 positions. One flat spring 35 is positioned near each free edge of the cover section and body or supporting section of the casing 1 and at spaced intervals, helical 20 springs 37 are provided which bear against the resilient bars 34 for supporting the intermediate portions of the rubber structure 30 in outermost positions. The provision of the flat springs 35, helical springs 36 and 37 25 permit of the yielding of the relatively stationary rubber 30 outwardly toward the casing 1 upon engagement against portions thereof of relatively thick articles being washed, consequently maintaining a firm 30 rubbing contact with the articles being washed, at all times.

The body 1 of the washing machine is preferably formed of wooden end pieces 40 which have sheets 41 of sheet metal attached thereto forming the sides of the body. One of the end disks 40 is provided with a drain opening 42 normally closed by a plug 43 to permit the draining of the detergent liquid from the body.

The supporting section 4 of the body 1 has angled metal strips 45 along its upper edge, the upstanding portions of which extend into suitable grooves 46 formed in the engaging surfaces of the ends of the top 50 section to provide a fluid tight connection between the hinged cover or top section of the body and the lower supporting section and the sheet metal 41 which is attached to the top or cover section 5 overlaps the adjacent edge of the body or supporting section at the hinged connection as clearly shown in Fig. 2 of the drawings.

The shaft 7 may have a power pulley indicated at 48 mounted upon one end of the same, through the medium of which pulley power may be transmitted to the shaft for rotating the same. This shaft 7 also has a gear 49 upon its opposite end which meshes with a relatively large gear 50 mounted upon a shaft 51 which is carried by

one end 40 of the body. The gear 51 may have a crank handle 52 attached thereto for manually rotating the same, or the shaft 51 may have a pulley indicated at 53 thereon by means of which power from any suitable 70 source may be transmitted to the shaft 51 for in turn imparting motion, in increased ratio, to the shaft 7 through the medium of the gears 49 and 50.

Having fully described the invention, what 75 is claimed is:

1. In a washing machine, a rotary rubber provided with a plurality of segments pivotally connected to the main body of the rotary rubber, and means for holding said 80 pivoted sections in adjusted positions for gripping articles to be washed.

2. In a washing machine, a rotary rubber comprising a plurality of spaced disks, said disks having segments cut therefrom and pivotally connected to the disks, corrugated plates extending across said disks and segments and forming a corrugated rubbing 85 surface for the rotary rubber.

3. In a washing machine, a rotary rubber 90 comprising a plurality of spaced disks, said disks having segments cut therefrom and pivotally connected to the disks, corrugated plates extending across said disks and segments and forming a corrugated rubbing 95 surface for the rotary rubber, and means for holding said pivoted sections in adjusted positions with respect to the facing edges of the disks to securely grip articles to be washed therebetween.

4. In a washing machine, the combination of a casing, a non-rotating rubber yieldably mounted within said casing, means for yieldably supporting said non-rotating rubber in its innermost position, a rotary rubber rotatably mounted within said casing and composed of a plurality of disks, segments cut from said disks and pivotally connected to the disks, sheets of corrugated 105 sheet metal attached to the peripheries of said disks and segments and forming a corrugated rubbing outer surface for the rotary rubber, and means for holding said pivoted segments in adjusted positions with respect to their respective disks for gripping articles 110 to be washed between the facing edges of the segments and disks.

5. In a washing machine, a rotary rubber provided with a plurality of segments pivotally connected to the main body of the rubber, means for holding said segments in adjusted position for gripping articles to be washed, and corrugated plates attached to the outer edges of said segments to form 115 rubbing surfaces.

6. In a washing machine, a rotary rubber comprising a main body portion, a plurality of segments struck from said body portion, and pivotally connected thereto, a rod carried by each segment and means car- 120 125 130

ried by the body portion for coaction with said rods to hold the segments in article gripping positions.

7. In a washing machine, a rotary rubber comprising a plurality of spaced disks, 15 segments struck from said disks in alining sets, and pivotally connected to the disks, a rod extending through the segments of each set and connecting them for synchronous movement, and means carried by certain of 20 said disks for engagement with said rods to hold the segments in adjusted positions for gripping articles to be washed, and corrugated plates attached to the outer edges of 25 said segments and extending across each set thereof to form rubbing surfaces.

8. In a washing machine, a rotary rub-

ber comprising a plurality of spaced disks, 15 segments struck from said disks in alining sets, and pivotally connected to the disks, a rod extending through the segments of each set and connecting them for synchronous movement, and means carried by certain of 20 said disks for engagement with said rods to hold the segments in adjusted positions for gripping articles to be washed, and corrugated plates attached to the outer edges of 25 said segments and extending across each set thereof to form rubbing surfaces.

JOHN BOTTs.
